DESIGN FOR A COMBINED STAND AND ELECTRIC FAN

Alfred F. Fukal, Cincinnati, Ohio, assignor to William W. Welch, Cincinnati, Ohio

Application June 26, 1941, Serial No. 101,696

Term of patent 7 years

To all whom it may concern:

Be it known that I, Alfred F. Fukal, a citizen of the United States, residing at Cincinnati, in the county of Hamilton and State of Ohio, have invented a new, original, and ornamental Design for a Combined Stand and Electric Fan, of which the following is a specification, reference being had to the accompanying drawing, forming a part thereof.

The characteristic features of my design reside in the portions shown in full lines.

I claim:

The ornamental design for a combined stand and electric fan, as shown and described.

ALFRED F. FUKAL.
